CLAIM

The ornamental design for a pinch clip occluder, as shown and described.

DESCRIPTION

FIG. 1 is a perspective view of a pinch clip occluder showing our new design;

FIG. 2 is a top plan view thereof;

FIG. 3 is a right side view (the left side being a mirror image thereof);

FIG. 4 is a front end view shown in a closed position; and, FIG. 5 is a front end view shown in an open position.

The broken lines showing the tube and the structure on the back end are for illustrative purposes only and form no part of the claimed design. The portions of the inside surfaces which are not visible follow the contour of the structure defining each inside surface. The undisclosed portions of the bottom, back end and inner coil element form no part of the claimed design.
